UNITED STATES PATENT OFFICE.

WILLIAM E. SEWELL, OF DETROIT, MICHIGAN.

DISINFECTING-CABINET FOR BARBERS' USE, &c.

SPECIFICATION forming part of Letters Patent No. 694,676, dated March 4, 1902.

Application filed April 22, 1901. Serial No. 56,907. (No model.)

To all whom it may concern:

Be it known that I, WILLIAM E. SEWELL, a citizen of the United States of America, residing at Detroit, in the county of Wayne and 5 State of Michigan, have invented certain new and useful Improvements in Disinfecting-Cabinets for Barbers' Use, &c., of which the following is a specification, reference being had therein to the accompanying drawings.

10 This invention relates to new and useful improvements in sterilizing or disinfecting cabinets for barbers' use, and has for its object to make a cabinet adapted to contain the disinfectant and the implements to be disinfected, whereby the implements are always accessible and the inlet of the disinfectant cut off while the implements are being removed or returned to the cabinet.

To this end the invention consists in the 20 employment of a cabinet having a series of valve-controlled compartments adapted to contain the implements to be disinfected and a separate compartment containing the disinfectant.

25 The invention further consists in the peculiar construction, arrangement, and combination of parts, all as more fully hereinafter described, and shown in the accompanying drawings, in which—

30 Figure 1 is a vertical central section. Fig. 2 is a section on the line 2 2 of Fig. 1. Fig. 3 is a perspective view of the cabinet.

As shown in the drawings, A is a cabinet formed at the bottom with a drawer B, in 35 which a glass or other suitable tray C is placed containing the disinfectant, a blotter or piece of felt being preferably laid in the tray, which is saturated with the solution.

D and E are horizontal partition-walls, the 40 partition-wall E extending but half-way across the cabinet and forming with the vertical partition-wall F a compartment G, adapted to receive a drawer G' for the reception of a hair-brush or the like, while the top compartment H is provided with a drawer H', extending entirely across the cabinet, for the reception of razors, &c. I may, however, have the compartment G extend clear across the cabinet, similar to the compartment H.

45 50 I is a chamber or compartment provided

with the drawer B, adapted to receive the vessel C, containing the disinfectant.

The drawers G' H' are made of a length slightly less than the cabinet, with their side pieces terminating in inclined cams beyond 55 the rear edge of the drawer proper, the drawer H' being preferably open at the back for the ready access of the disinfectant, a ridge a being formed at the back to form an abutment for the razors, while the drawer G' is provided with a back b, preferably extending to near the bottom to form a transverse slot c beneath the same for the admission of the disinfectant.

d is an opening in the bottom of the drawer 65 G', registering with an opening d' in the partition-wall E when the drawer is pushed in, and e is an opening in said wall provided with a hinged valve f, extending entirely across the compartment, so that when the drawer is 70 pushed in the inclined cams g will strike the valve f and lift it from said opening, the openings d d' registering at the same time, so that the disinfectant will circulate through the opening e, slot c, and into the compartment G', thence through the openings d d' 75 into the chamber I.

h is a hole in the partition-wall D, provided with a hinged valve i, extending entirely across the compartment, and j represents inclined cams formed on the drawer H', adapted to coöperate therewith to lift the valve from its seat, similar to the valve f.

The bottom of the drawer H' is spaced a slight distance from the partition-wall D, and 85 k represents a series of transverse slots in the bottom to permit the free circulation of the disinfectant therethrough, and l is a cloth lining to prevent injuring the razors. The drawer G' may be similarly lined, as shown. 90

I am aware that it has been proposed to place a razor in a vessel containing a liquid disinfectant or in a chamber in which the disinfectant is heated; but I have found that both of these methods either corrode the razor or spoil its cutting edge, while with my construction this objection is entirely overcome, as the razors do not come in contact with the liquid or saturated steam therefrom. 95 It will also be noticed that each of these com- 100

partments is in independent communication with the disinfectant-chamber, and as soon as either drawer is drawn out it is cut off from the source of supply, thus preventing 5 the escape of the disinfectant into the room.

Any disinfectant may be used which will destroy bacteria or micro-organisms, as such disinfectants have been found very penetrating, and it would be impossible for a germ to 10 live in such a cabinet.

What I claim as my invention is—

1. The combination in a disinfecting or sterilizing cabinet, of a casing divided into compartments by transverse partition-walls 15 formed with openings, drawers fitting in said compartments, valves controlling the openings in said partition-walls, for controlling communication between the compartment for the disinfectant and the compartments adapted 20 to contain the articles to be disinfected, and inclined cams carried by said drawers for actuating its particular valve to establish communication with the compartment containing the disinfectant.

2. In a disinfecting-cabinet, the combination of a casing divided by transverse partition-walls into an upper, a lower and intermediate compartments, communicating through openings in said partitions with the 30 lower compartment, valves controlling said openings, drawers fitting in said compartments, inclined cams carried by said upper and intermediate drawers for opening said valves when the drawers are pushed in, and 35 the intermediate drawer formed with the opening *d* in its bottom adapted to register with the opening *d'* in the lowermost partition-wall.

3. The combination in an apparatus of the character described, of a casing divided into 40 compartments by partition-walls formed with openings, drawers fitting in said compartments, valves controlling the openings in said walls, means for actuating said valves by the movement of the drawers, one of said drawers 45 having a second set of openings or apertures formed in its bottom and inner end in communication with the source of disinfectant-supply, whereby a circulation of the disinfectant is obtained throughout the full length of the 50 drawer.

4. In a disinfecting-cabinet, the combination of a casing divided by transverse partition-walls into an upper, a lower and intermediate compartment, communicating 55 through openings in said partitions with the lower compartment, valves controlling said openings, drawers fitting in said compartments having stops or abutments across their rear ends of a width less than the height of 60 the drawer to form transverse openings for the admission of the disinfectant into the drawer and means carried by the drawers for opening said valves at an angle to deflect the disinfectant into the ends of said drawers.

5. In a disinfecting-cabinet, the combination of a casing divided by transverse partition-walls into an upper, a lower and intermediate compartment, said upper and intermediate compartments communicating with the compartment adapted to contain the disinfectant through openings in said walls, valves controlling said openings and drawers fitting in said compartments, means carried by said drawers for actuating said valves, said intermediate drawer having an opening 75 formed in its forward end coinciding with an opening in the partition-wall and a stop or abutment extending across the rear end of said drawer, of a width less than the height of the drawer to form a transverse opening 80 beneath the same, whereby a circulation of the disinfecting medium is obtained throughout the entire length of the drawer.

6. In a disinfecting-cabinet, the combination of a casing divided by transverse partition-walls into an upper, an intermediate and a lower compartment adapted to contain the articles to be disinfected and the disinfectant respectively, the upper and intermediate compartment communicating with the compartment containing the disinfectant through openings formed in said walls, valves controlling said openings and drawers fitting in said compartments, inclined cams carried by said upper and intermediate drawers for opening said valves when the drawers are pushed in, said upper drawer having its bottom slitted and raised above the partition-wall to form an air-space therebetween whereby a circulation of the disinfectant is obtained. 95

7. The combination in an apparatus of the character described, of a casing divided into compartments by partition-walls, drawers fitting in said compartments, flap-valves hinged to said partition-walls adjacent to openings 105 formed therein, inclined cams formed by a rearward extension of the side members of said drawers for opening said valves when said drawers are pushed in and hold the same in an inclined position to deflect the disinfectant into said drawers. 110

8. In a device of the character described, the combination with a casing of transverse partition-walls dividing the same into compartments communicating with each other 115 through openings in said partition-walls, drawers fitting in said compartments, valves controlling the openings in said partition-walls, and coacting inclines on the valves and drawers adapted to open the valves by the 120 closing movement of the drawers.

In testimony whereof I affix my signature in presence of two witnesses.

WILLIAM E. SEWELL.
